[57] CLAIM

The ornamental design for an osteotomy blade, as shown and described.

DESCRIPTION

FIG. 1 is a perspective view of an osteotomy blade showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view of an alternate embodiment of the design shown in FIG. 1;

FIG. 9 is a front elevational view of FIG. 8;

FIG. 10 is a rear elevational view of FIG. 8;

FIG. 11 is a right side elevational view of FIG. 8;

FIG. 12 is a left side elevational view of FIG. 8;

FIG. 13 is a top plan view of FIG. 8 and,

FIG. 14 is a bottom plan view of FIG. 8.

Fig. 4

Fig. 5.
